A. RUMRICH

BURGLAR ALARM

Filed Aug. 5, 1926

Patented May 17, 1927.

1,629,312

UNITED STATES PATENT OFFICE.

ALFONS RUMRICH, OF PITTSBURGH, PENNSYLVANIA.

BURGLAR ALARM.

Application filed August 5, 1926. Serial No. 127,412.

The invention aims to provide a new and improved device which may be made to effectively sound an alarm, if an attempt is made to open a door or window which is 5 equipped with the device.

A further object is to provide novel means whereby the alarm may be made to sound only while an attempt is being made to open the door or window equipped with it, or may 10 be set in operation by such attempted forcing and will continue to ring until reset by a person within the building.

A still further object is to provide an alarm device designed primarily for use in connection with doors and of such construction that it will be sounded either by turning the door 15 knob or by exerting pressure upon the door, attempting to force it open or attempting to drill the same for the purpose of releasing 20 its lock.

With the foregoing and minor objects in view, the invention resides in the novel subject matter hereinafter described and claimed, the description being supplemented 25 by the accompanying drawing.

Fig. 1 is a vertical sectional view through the invention showing it applied to a door and door frame.

Fig. 2 is a front elevation of the device 30 with the casing removed, parts being broken away and in section.

Figs. 3, 4 and 5 are detail horizontal sectional views on the plane of line 3—3 of Fig. 1, showing different positions of parts which 35 will be hereinafter described.

Fig. 6 is a small diagrammatic view illustrating the manner of applying the invention to a door.

Fig. 7 is a detail sectional view partly in 40 elevation illustrating the manner in which the control member is permitted to move to the maximum, whereas such movement is not permitted in Fig. 2.

Fig. 8 is a fragmentary vertical section 45 similar to a portion of Fig. 1 but illustrating a modified form of construction.

The drawings above briefly described, may be considered as disclosing the preferred form of construction, it being understood 50 however that within the scope of the invention as claimed, variations may be made.

The numeral 9 designates a back plate 55 secured to a door 10 by screws 11, said back plate projecting beyond an edge of the door, said edge being preferably the upper edge.

This projecting portion of the back plate 9 is formed with an opening 12, and a stud 13 passes loosely through this opening and projects forwardly from the plate 9. In the present showing, the stud 13 is provided with 60 a screw threaded portion 14 which is threaded into a small board or the like 15, the latter being secured by screws or other desired means 16 to a portion of the door frame 17.

A spring-actuated alarm mechanism 18 is 65 suitably mounted upon the front side of the back plate 9, the spring of said mechanism being indicated at 19 and its winding key at 20. This mechanism includes a suitable escapement 21 for operating a clapper 22, the 70 latter preferably co-acting with two bells 23 mounted on the plate 9. Any suitable device 24 may be employed to hold the clapper 22 against operation whenever desired, and the shaft 25 upon which this clapper is 75 mounted, is provided with an arm 26 which prevents actuation of the alarm mechanism, as long as said arm is held. Novel provision is made for normally holding this arm but for releasing it at the proper time. 80

A control lever 27 is fulcrumed between its ends at 28 upon the front side of the back plate 9, said lever having an angular end 29 which normally engages the arm 26 to hold the latter against movement, thus preventing movement of the clapper 22. A spring 30 is connected with the lever 27 so as to normally hold the latter in the operative position shown in Fig. 2, the movement of the lever in either direction being limited by an appropriate yoke 31. This lever 27 is provided with a resilient lower portion 32 which normally abuts the outer end of the stud 13, so that said lower portion of the lever is held 90 outwardly away from the back plate 9, as seen in Fig. 1. Should pressure be exerted on the door 10 however in the direction of the arrow A (Fig. 1), such pressure would separate the back plate 9 from the board or the like 15, as seen in Fig. 4, and upon such an occurrence, the stud 13 would no longer project beyond the front surface of the plate 9, the result being that the resiliency of the lever portion 32, would cause said portion to move toward the back plate as will be clear from Fig. 4. This movement disengages the angular end 29 of the lever 27, from the arm 26 and permits the clapper 22 to operate. 95

Thus, it will be seen that if an attempt is made to force the door open or if said door 100 is moved to the right, the lever 27 will move to the left, the lower portion 32 of the lever 27 105 being urged to the left by the resiliency of the portion 32, and the angular end 29 will move to the right, thus disengaging the angular end 29 from the arm 26, and permitting the clapper 22 to operate. 110

should be moved in the direction of the arrow A, by an attempt to drill through to the lock, the alarm will be sounded.

By means of any desired flexible line 35, the upper end of lever 27 may be connected with an arm 36 on the knob shaft of the door 10, said line being passed through an appropriate guide 37, said guide being appropriately mounted upon said door. Thus, if the door knob is turned in an attempt to open the door, the line 35 will be pulled, thus swinging the lever 27 to free its lower end 29 from the arm 26, permitting sounding of the alarm. If this lever is moved as far as the dotted line position of Fig. 2, it will snap past the projecting end of the pin 13 so that it is held against movement to its normal position, under the influence of the spring 30. However, if the lever 27 is not permitted to move this far, it will return to the normal full line position of Fig. 2, as soon as the knob is released. In order that the lever may be permitted to move either to one position or the other, as desired, I provide a rotatable member 38 turnably mounted upon the plate 9 and having a notch 39. When this member 38 is set as shown in Fig. 2, the lever 27 cannot swing sufficiently far to be locked against return movement, by the stud 13. When the member 38 is turned to the position of Fig. 7, the upper end of the lever 27 may move into the notch 39, permitting said lever to turn to the dotted line position of Fig. 2, in which position it will engage the stud 13, so that it is locked against return movement by said stud, the result being that the alarm will operate until someone from the inside of the building resets the device.

It will be seen from the foregoing that while the invention is rather simple and inexpensive, it will be efficient and in every way desirable, as when it is used upon a door, it sounds an alarm when the knob is turned or when attempt is made to force or drill the door. Fig. 3 of the drawings discloses the normal position of the lever end 29 to hold the arm 26 against operation, but Fig. 4 illustrates the manner in which said arm is released when the door is inwardly forced from the frame and the lever 27 consequently springs toward the back plate 9. Fig. 5 illustrates the manner in which the lever 27 snaps into engagement with the stud 13 to be locked by the latter against return movement, when swinging of the lever to this extent is permitted by setting of the device 38, in the manner shown in Fig. 7.

Fig. 8 illustrates a slightly different form of construction, in which a stud 13^a, instead of being rigidly carried by a board or the like such as 15, is loosely mounted in an opening 12^a in the back plate 9^a, said pin coming in contact with the nail, screw or the like 14^a driven into the door frame 17^a when

the door 10^a is closed. The pin 13^a is thus outwardly forced to hold the lower end 29^a of lever 27^a in engagement with the arm 26^a. When the door is forced away from the frame, the end 29^a of the resilient lever 27^a disengages from the arm 26^a and permits operation of the alarm, it being understood that this arm 26^a and the lever 27^a are identical with the parts 26 and 27 above described.

As excellent results may be obtained from the details disclosed, they are preferably followed. However, within the scope of the invention as claimed, numerous modifications may be made.

Attention may further be directed to the fact that the invention may act also as a door bell, as it will operate simply by turning the knob to a slight extent.

I claim:

1. In a burglar alarm, an alarm-sounding mechanism, a movably mounted control member normally engaged with said alarm-sounding mechanism to prevent functioning thereof, said control member having two released positions at which it permits operation of the alarm-sounding mechanism for a short period or continuously respectively, common means connected to said control member for moving it to either of said positions, means for returning said control member to its normal position when moved to one of said released positions, manually set means for limiting the movement of said member to said one position if desired, and means for holding said member against return to its normal position when moved to its second released position at which the alarm sounds continuously.

2. In a burglar alarm, an alarm-sounding mechanism, a pivotally mounted control member normally engaging the alarm-sounding mechanism to hold the same against functioning, said member being swingable in the same direction to either of two released positions at which it permits sounding of the alarm for a short period or continuously, respectively, a spring acting on said member to return it to its normal position when moved to its first released position, manually set means for limiting the movement of said member to said first released position if desired, and means for holding said member against return to its normal position when moved to its second released position at which the alarm sounds continuously.

3. In a burglar alarm, an alarm-sounding mechanism, and a control member normally engaging said alarm-sounding mechanism to hold it against functioning, said member being movable on either of two distinct paths to release said alarm-sounding mechanism, whereby said member may be operatively related with a closure to be released by

either of two independent movements thereof.

4. In a burglar alarm, an alarm-sounding mechanism, a control member normally engaging said mechanism to hold it against functioning, means mounting said member for movement on one path to a released position, said member being resilient to permit it to spring to a second released position in a direction transverse to said path, means operatively connected with said control member for effecting movement thereof on said path, and additional means stationary with respect to and normally abutting said control member to normally prevent springing of said member to said second released position.

5. In a burglar alarm, a back plate, an alarm-sounding mechanism thereon, a lever fulcrumed between its ends to said back plate and having one end normally engaged with said mechanism to prevent functioning

thereof, means connected to said lever to swing it about its fulcrum to a released position, said lever having a resilient portion permitting it to spring transversely of its plane of swinging movement to a second released position, said back plate having an opening normally covered by said one end of the lever, and a pin passing movably through said opening and projecting forwardly from said back plate to normally engage said one end of said lever and hold it against springing to said second released position.

6. A structure as specified in claim 5; said one end of said lever being adapted to spring into locking engagement with said pin when said lever is swung to the first named released position, whereby it is held against return to its normal position.

In testimony whereof I have hereunto affixed my signature.

ALFONS RUMRICH.
